UNITED STATES PATENT OFFICE.

BERTRAM E. MORELAND, OF CHICAGO, ILLINOIS, ASSIGNOR TO THE MORELAND ADVERTISING COMPANY, OF CHICAGO, ILLINOIS, A CORPORATION OF ILLINOIS.

ADVERTISING DEVICE.

1,238,177.

Specification of Letters Patent. Patented Aug. 28, 1917.

Application filed March 3, 1917. Serial No. 152,202.

To all whom it may concern:

Be it known that I, BERTRAM E. MORELAND, a citizen of the United States, and a resident of Chicago, in the county of Cook and State of Illinois, have invented certain new and useful Improvements in Advertising Devices, of which the following is a specification.

My invention relates to advertising devices, particularly to that class in which a sheet of comparatively heavy paper has a communication or advertisement written thereon and is then folded to form a mailing inclosure or envelop and which also supports and conceals a return postal card.

Advertising devices of this class have been made (see my Letters Patent No. 1,204,584, of November 14, 1916) in which a gummed strip or paster extends through a slot in one of the folding edges of the sheet to serve at its inner end to support the return card and to serve at its outer end for sealing the folded sheet. With this arrangement, the return card, after opening of the inclosure, is removed by tearing the inner end of the paster so that a part of the paster remains on the card, this giving the card an unsightly appearance. Furthermore, the paster is only of a single thickness where it folds over the edge of the folded sheet, and it becomes worn during passage through the mails and oftentimes torn before the communication reaches its destination.

The object of my invention is to provide a more practical and efficient means for supporting the return card and for strengthening the supporting paster. This I preferably obtain by providing an extension or tab on the card separated from the card body by a line of perforations so that it can be readily torn away, and looping the inner end of a paster through one of the perforations, the paster loop being of sufficient length to provide double walls where it passes through the slot and is folded. With this construction the paster resists wear and tear during transit through the mails and when the communication is opened the tab is torn from the card and takes with it the paster end so that the card has its natural neat appearance.

The various features of my invention are embodied in a structure disclosed on the accompanying drawing, in which drawing—

55 Figure 1 is a perspective view showing

the sheet just before final folding and sealing thereof.

Fig. 2 is a side elevational view of the sealed communication with parts broken away, and

60 Fig. 3 is an enlarged sectional view on plane 3—3, Fig. 2.

In the arrangement shown, a rectangular sheet of comparatively heavy paper is creased along the lines 10 and 11 to form the middle and end sections 12, 13 and 14, advertising or other communication printing appearing on the inside of the sections, and the sheet being closed by folding down the top section 13 and folding up the lower section 14, thus forming a mailing envelop or inclosure for the communication. The return card 15 is usually of ordinary postal card size and in accordance with my invention this card has the extension or tab 16 at its upper edge separated from the card body by perforations 17 which enable the tab to be readily torn from the card. A gummed band or paster 18 has its inner end inserted through one of the perforations and folded to bring its gummed surfaces together to form the loop 19 whereby the paster is secured to the card. Before folding the communication sheet the outer end of the paster is inserted through the slot 20 in the folding line 10, and then after the card sections are folded together, such outer end of the paster is brought downwardly and pasted against the outer section 14, the end of the paster being preferably enlarged, as indicated at 21. When forming the loop 19 a sufficient length is folded to provide a double wall or thickness where the paster extends through the slot 20 and where the paster is folded over to bring its end 21 into sealing engagement with the folded sheet. The paster has therefore double strength at this point and will resist wear during passage through the mails and will not tear. Preferably the section 14 of the sheet is of slightly less width

90 than the other sections so that when folded its edge 22 will be below the folding line 10, and the fold for the loop 19 is of such length that the double thickness of the paster will extend only as far as the edge 22. Such double thickness between the folding line 10 and the edge 22 will prevent the paster from bending sharply around the edge 22 and wearing or cutting of the paster at that point. The envelop can readily be 100 105 110

opened by tearing the single thickness of 5
paster along the edge 22. After opening
and unfolding the return card with the
paster stub thereon is withdrawn and the
tab 16 and the paster stub removed by tear-
ing along the perforations 17. The return
card is then of ordinary and neat appear-
ance. If the return card is torn from the
tab while passing through the mails the tab
10 16 serves as a locking member to hold the
sections of the device together.

Having described my invention, I desire
to obtain the following claims by Letters
Patent:

- 15 1. A device of the class described com-
prising a sheet of paper folded to form a
mailing envelop and having a slit, a return
card having a tab separated from the card
body by a line of perforations, and a sealing
paster secured at its inner end to said tab
20 and having its outer end extended through
said slit to be folded over against the outer
folded section of the sheet to seal the
envelop, said perforations adapting said tab to
25 be readily torn from the card body after
opening of the envelop and said tab prevent-
ing the unfolding of the mailing envelop in the event of accidental separation
of the card.
- 30 2. A device of the class described com-
prising a sheet of paper for receiving a
printed communication on its inner face and
for being folded to form a mailing envelop
and having a slit, a return card for the
35 envelop, a tab on said return card separated

from the card body by a line of perforations
and serving as a locking bar, a sealing paster
looped at its inner end through one of said
perforations and having its outer end ex-
tended through said slit to be folded over 40
and secured to the outer folded section of
the sheet to seal the envelop.

3. A device of the class described com-
prising a sheet of paper for receiving
printed communication on its inner face and
45 to be folded to form a mailing envelop and
having a slit, a return card having a tab
separated from the card body by a line of
perforations, a paster having its inner end
inserted through one of said perforations 50
and folded over with its gummed surfaces
secured together to form a supporting loop
for the card, the outer end of said paster
extending through said slit to be folded over
55 and secured to the outer folded section of
the envelop to seal the envelop, said loop
being of sufficient length to provide double
thickness for the paster where it passes
through the slit and where it is folded into
60 sealing position, said perforations enabling
the tab and loop end of the paster to be
readily removed from the card body after
the envelop has been opened and said tab
preventing the unfolding of the mailing
65 envelop in the event of the accidental separa-
tion of the card.

In witness whereof I hereunto subscribe
my name this 27th day of February, A. D.
1917.

BERTRAM E. MORELAND.
